US0D1015223S

(12) **United States Design Patent** (10) **Patent No.:** **US D1,015,223 S**
(45) **Date of Patent:** **** Feb. 20, 2024**

(54) **ELECTRIC BICYCLE**

(71) Applicant: **SHENZHEN CHIRREY TECHNOLOGY CO., LTD**, Shenzhen (CN)

(72) Inventor: **Jun Zhang**, Hubei (CN)

(**) Term: **15 Years**

(21) Appl. No.: **29/903,573**

(22) Filed: **Sep. 26, 2023**

(51) **LOC (14) Cl.** **12-11**

(52) **U.S. Cl.**

USPC **D12/111**

(58) **Field of Classification Search**

(57) **CLAIM**

The ornamental design for an electric bicycle, as shown and described.

DESCRIPTION

FIG. 1 is a top, front, and left side perspective view of an electric bicycle embodying my new design;

FIG. 2 is a bottom, rear, and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a partial and enlarged perspective view of area 9 in FIG. 1.

The broken lines in the drawings illustrate portions of the electric bicycle that form no part of the claimed design.

1 Claim, 9 Drawing Sheets
